UNITED STATES PATENT OFFICE.

CHARLES VINCENT RAPIER, OF PARIS, FRANCE.

DEVICE FOR SWITCHING UNIVERSAL CRANES.

Application filed August 31, 1922. Serial No. 585,490.

To all whom it may concern:

Be it known that I, CHARLES VINCENT RAPIER, engineer, a subject of the King of Great Britain, residing at 39 Rue Victor 5 Massé, Paris, France, have invented new and useful Improvements in Devices for Switching Universal Cranes, of which the following is a specification.

The present invention relates to devices 10 for switching universal travelling cranes running upon overhead runway tracks. It is known that these universal cranes are constituted, in principle, by two trolleys or two groups of trolleys coupled together 15 which run upon the overhead tracks of the transporter used with the ordinary trolleys, each trolley or group of trolleys carrying one of the extremities of a girder which constitute a run-way for a trolley carrying the 20 load.

Cranes of this kind can move upon two tracks which may be parallel, straight or curved, can enter into switches, pass over crossings and differences in level of the 25 track, can pass from one span to another, the girder of these cranes being capable of moving either laterally or longitudinally relative to itself.

All these movements were effected up to 30 the present by imparting to the load suspended from the girder the impulses necessary in order to cause the trolleys to engage the switches, but the operations effected in this manner do not take place in a positive 35 and sure manner.

The present invention relates to devices which permit of obtaining in a positive and certain manner the switching of the two trolleys or groups of trolleys situated at the 40 end of the crane without it being necessary to provide a movable switch in the track.

These devices are characterized by the fact that they comprise a manually actuated device at each extremity of the crane which 45 serves to determine the direction of the trolleys, a mechanical connection between these two devices, so as to enable said device to be actuated from one or the other of the ends of the crane, and a guide mechanism at each 50 end of the crane acting upon the trolleys of these ends under the influence of the actuating devices in question.

Various forms of construction of these devices are described below by way of example

and are shown in the diagrammatic drawings annexed in which:

Fig. 1 is a side view of the end of a universal crane having a double trolley or bogie running upon a double-rail system with a guiding mechanism having a spring under compression.

Fig. 2 is a front view corresponding to Fig. 1.

Fig. 3 is a general view of a universal crane constructed according to Figs. 1 and 2.

Fig. 4 is a side view similar to Fig. 1 but comprising a guiding mechanism having a spring under tension.

Fig. 5 is a plan view of a portion of the tension-spring mechanism.

Fig. 6 is a front view corresponding to Fig. 4.

Fig. 7 is a side view of a bogie of a universal crane having a guiding mechanism comprising a roller and fixed cam guide.

Fig. 8 shows a modification of the method of actuation of this guiding mechanism.

Fig. 9 is a general view of a crane constructed according to Fig. 7.

Fig. 10 is a detail of Fig. 9.

Fig. 11 is a plan view showing the method of operation of a universal crane according to Figs. 7, 8 and 9.

Fig. 12 shows a modification of the guide mechanism provided with a roller and fixed cam guide.

Fig. 13 shows a detail of the guide mechanism of Fig. 11.

Fig. 14 is a side view of a bogie of the universal crane provided with a guide mechanism having differential levers.

Fig. 15 is a section along line 15—15 of Fig. 14.

Fig. 16 is a detail of the guide mechanism of Fig. 14.

Figs. 17 to 27 inclusive are views similar to Figs. 1, 2, 3, 4, 6, 7, 8, 11, 12, 14 and 15 respectively, but they relate to universal cranes having a double trolley or bogie running upon a mono-rail track.

Fig. 28 is a side view of the extremity of a universal crane having a single trolley running upon a two rail track and provided with a guiding mechanism having a spring under compression.

Fig. 29 is a front view corresponding to Fig. 28.

Fig. 30 is a general view of a universal

2 crane constructed according to Figs. 28 and 29.

Fig. 31 is a section along line 31—31 of Fig. 30.

5 Fig. 32 is a side view of a trolley of a universal crane having a guide mechanism comprising a roller and a guiding incline.

Fig. 33 is a view similar to Fig. 32 but comprising a modified form of guide mecha- 10 nism.

Fig. 34 is a general view of a universal crane having one single trolley at each end of the double rail type with an elastic connecting mechanism between said trolleys.

15 Fig. 35 is a detail of the connecting mechanism of Fig. 34.

Fig. 36 shows a side view of the end of a universal crane having a single mono-rail trolley and comprising a guiding mechanism having a spring under compression.

20 Fig. 37 is a front view corresponding to Fig. 36.

Fig. 38 is a side view of a single trolley of a universal crane having a guiding mechanism provided with a roller and a fixed cam 25 guide.

Fig. 39 is a view similar to 38 showing a modification of the guiding mechanism.

Fig. 40 is a view similar to Fig. 34 but 30 applied to the case of a mono-rail system.

Fig. 41 shows by way of example the application of one of the switching systems according to this invention to the case of a crane comprising four trolleys at each 35 extremity.

Figure 42 is a diagram showing the method of operation of a universal crane.

For a clear understanding of the present 40 invention, a description of the method of operation of a universal crane will first be given with reference to Fig. 42. This figure gives a plan view of a system of runway track of the double rail type comprising a track *a* to which branches at right angles *b* are connected by the intermediary 45 of switches *c*. All these branches are at equal distances apart and the junctions are preferably curved to the same radius.

Taking the case of a universal crane *e*, 50 *d*, *e* serving a span comprised between two branches *b*, if the bogies *e* pivot relatively to the cross girder *d*, it will be understood that the universal crane *e*, *d*, *e* can be brought into the junctions of the sidings, into the 55 position *d*¹ and that the bogies *e* can be caused to engage in the switches so as to move one behind the other on the central track *a*. The universal crane can thus be brought to the position *d*² from which, by 60 an operation the reverse of that which has been described, it can be caused to enter any desired siding. The universal crane *e*, *d*, *e* can also be brought to the position *d*³. The purpose of the present invention is to en-

sure the switching of universal cranes 65 through junctions.

Referring now to Figs. 1 to 16, 1 and 2 are two trolleys connected together by a chain or other similar coupling and constituting the bogie which supports one of 70 the extremities of the main girder of a universal crane 3 constituted, in the examples shown, by two U joists placed back to back. These trolleys run upon a double rail track 4 and, by means of bolts 5, carry 75 a box 6 formed by two U joists connected together one opposite the other. At the middle of the box 6 is fitted a bolt 7, the head of which rests, through the intermediary of a thrust bearing 8, upon a spherical abutment 9 formed in a plate 10 fixed to the box 6. The lower portion of this bolt 7 is screwed into a sleeve 11 having gudgeons 12 which can pivot in the body of the U joists of the girder 3. A lock-nut 13 enables the bolt 7 and the sleeve 11 to be locked together. A trolley 14 of the mono-rail type runs upon the girder 3 and carries the load in any suitable manner.

The method of suspension of the girder 90 3 just described is for the purpose of ensuring liberty of relative movements of said cross girder and the bogies when passing over curves and switches, which greatly diminishes the torsional, shearing and other 95 stresses to which otherwise the bolts 7 would be subjected.

The guide mechanism having a compression spring according to Figures 1 to 3 is constructed in the following manner: the 100 suspension bolt 7 serves as an axis of rotation for the two sprocket wheels 15 and 16 which are fixed to each other and are free to rotate about the bolt 7. These wheels are arranged between the box 6 and the 105 girder 3. To wheel 15 is fixed a diametrical arm 17 the extremities of which are bent upwardly. These extremities are each traversed by a double headed abutment 18. A helical spring, such as 19, is interposed 110 between each of the heads and the extremity of the arm 17. All the springs 19 are of substantially the same strength so that the abutments 18 project substantially by the same amount on each side of the extremity 115 of the arm 17. The abutments 18 can bear against the lugs 20 suitably fixed on the trolleys 1 and 2. Endless chains 21 guided by sheaves 22 pass over the wheels 16 at each end and extend to a height of about one 120 metre from the ground. The wheels 15 are connected together by an endless chain 23 which, with the wheel 15, constitutes a connecting system between the manually operated devices, which exist at each end of the 125 crane, and which are operated by the chains 21, in such a manner that the guide mechanisms can be actuated from either end of

the crane. The endless chain 23 passes through protecting tubes fixed to the upper portion of the crane.

The method of operation is as follows:

- 5 Supposing that the crane moves from left to right in Fig. 1 and that it is desired to cause it to enter a switch situated on the right of its direction of movement, the chain 21 is pulled so as to cause the forward abutment 10 18 to bear against the left-hand face of the lug 20 of the trolley 2, at the same time compressing the corresponding spring 19. As soon as the trolley 2 reaches the switch, 15 the spring 19 pivots this trolley towards the right and compels it to take the desired direction. The same movement is effected at the other extremity of the crane owing to the connecting chain 23.

It is evident that by a suitable operation 20 it would be possible to switch the trolleys of the crane in all directions whatever may be the direction of movement of the crane.

The guide mechanism of Figs. 4, 5 and 6 is slightly different in that the wheels 15 25 and 16 are fixed to a frame 24 which envelops the box 6, while at the same time being capable of oscillating about the pivot 7 to an extent somewhat greater than a quarter of a revolution. On its upper face 30 this frame carries four pins 25, 25', 26, 26' (Fig. 5) arranged symmetrically to the axis of rotation of the frame 24. Between the pins 25 and 26 on the one hand and 25', 26' on the other hand, there is inserted a helical spring 29 which is slightly tensioned, 35 when the trolleys 1 and 2 are in line, between rods 27 and 28 fixed to the trolleys 1 and 2 respectively. This spring also acts as a coupling between the two trolleys constituting the bogie.

The method of operation is as follows:

If by means of the manipulating and connecting chains rotation is imparted to the frame 24 (Fig. 5) in the direction of the arrow f , the pins 25, 25' move to 25^a and 25^b respectively and tension the coil spring 29 by exerting a pull upon the rods 27, 28, the effect of which is to cause the two trolleys to assume a position corresponding to that shown by the arrows f' , f'' so as to effect switching in the corresponding direction.

In the form of execution shown in Figs. 7 to 13 inclusive the guide mechanism 55 is constituted by rollers 30 mounted upon rods 31 which can be raised vertically in such a manner as to cause the rollers to come into contact with fixed cams 32 fixed above the track and which cause the trolleys 60 to deviate towards the branch line. These cams do not act upon the rollers 30 when these latter are not raised, since in this case the rollers 30 pass underneath the cams. The method of action of the cams upon the

rollers will be evident from an examination of Fig. 11.

The vertical movement is communicated to the rollers 30 by levers 33 (Fig. 7) pivoted at 34 in the box 6 and provided with counterweights 35 at their outer ends, these levers being considerably wider than the rods 31 which rest upon them, with a view to taking care of the lateral movement of the rods 31 relative to the levers 33. The inner ends of these levers 33 are connected 75 by means of links to the extremity of a cable 36 passing through a longitudinal hole formed in the axis of the suspension bolt 7. This cable then passes over pulleys 37, 38 and 39 (Fig. 9) and goes to the other end 80 of the crane where it is arranged in the same manner and is attached to the actuating levers for the rollers of this other extremity. The cable 36 constitutes the mechanical connecting device between the 85 two guide mechanisms. The method of actuation is as follows: At the point 40 of the cable 36, between the pulleys 37 and 38, there is fixed one of the extremities of a chain 41, 42 the loop of which falls to about 90 one metre from the ground. One end is fixed to the crane 3 at a point 42'. The fall of the chain fixed at 42' merely serves to pull the crane 3 along the track, while the fall of the chain 41 serves for switching purposes.

The method of operation is as follows: If the fall of the chain 41 which is fixed at 40 to the cable 36 is pulled down to its fullest extent, the rollers 30 are caused to 100 rise and when they encounter the cam 32 they cause the crane to deviate towards the branch line.

It is preferable that the point 40 be located nearer to the pulley 37 than to the 105 pulley 38, for the reason that, during the first portion of the pull upon the chain 41, the rollers 30 situated near that end of the crane where the chain is situated, are raised, while the rollers 30 of the other end do not 110 rise, owing to the slack which exists in the portion of the cable 36 which is comprised between the two pulleys 39. When the chain 41 is then pulled to its fullest extent, the rollers 30 are caused to rise at the two 115 ends of the crane. The first operation will permit of the passage of the entire crane from one main track to a side track while the second will permit of the passage of the crane from a main track to a span 120 formed by two parallel tracks, upon which the crane will move parallel to itself.

In order better to control the sequence of these operations, the fall portion of the chain 41 can be connected to a stop mechanism, such as the slide 43 in the notches of which the spring plunger 44 can engage. The lower notch 45 corresponds to the neu-

tral or lowest position of the rollers 30, the middle notch 46 corresponds to the raising of the rollers 30 on the side only of the chain which is actuated, and the upper notch 47 corresponds to the raised position of the roller at both extremities of the crane.

Fig. 8 shows a modification of the mechanism for actuating the rollers 30. The rods 31 on which these rollers are mounted, 10 are pivoted freely at their lower ends upon the shaft 48, which can slide freely in elongated openings in two similar levers 49 pivoted at 50. These levers are situated on each side of the suspension bolt 5 and can 15 turn about the shafts 50 of these latter in the box 6. The levers 49 are pivoted with a certain amount of play at two diametrically opposite points of a member 51, which can oscillate about a rod 52 between two 20 shoulders of this latter. The rod 52 passes through an axial hole in the suspension bolt 7 and is pivoted at its lower portion upon a lever 53 which is hinged at a point 54 to the main girder 3 of the crane. The lever 53 is provided with a chain 55 one of the 25 ends of which is fixed to a point 56 of the crane girder 3 and serves to move the crane. The lever 53 is provided with a counterweight 57 which tends to cause the rod 52 to rise. Upon the extremity of the lever 53 which carries the counterweight 57, there is 30 hinged a lever 58, in an eye 59 of which there engages a pin carried by a crank 60 keyed upon a shaft 61 mounted longitudinally relative to the girder 3. At its other extremity the shaft 61 carries a crank similar to the crank 60 and is connected to the mechanism at the other end of the crane which is identical with that which has just 35 been described.

The method of operation is as follows:

A pull upon the chain 55 causes the rollers 30 to rise. During the first portion of their path these rollers are raised to a sufficient 45 extent to enable them to come into contact with the guide incline 32 (Fig. 9). However, during this first portion of the movement, the eye 59 slides upon the pin of the crank 60 without moving this latter. If 50 the pull upon the chain 55 is continued the rollers 30 rise more and more and the crank 60 is actuated in such a manner that the shaft imparts a rising movement to the rollers 30 of the other extremity of the crane. 55 The reason for this movement being effected in two stages has been explained with relation to Fig. 7.

In the device shown in Figs. 12 and 13 wheels 15 and 16 are fixed to a rotary cam 60 62 which has the form shown in plan in Fig. 13. This rotary cam acts upon the extremities of two levers 63 pivoting at 64 in the box 6, the extremities of which are provided with counterweights 65 and act 65 upon the rods 31 which carry the rollers 30.

Figures 14, 15 and 16 show a guiding mechanism having differential levers. The trolleys 1 and 2 are provided laterally with rigid arms 66 and 67 arranged opposite each other; these arms are each connected by 70 means of links 66', 67' to one of the extremities of the lever 68, the shape of which is shown in elevation in Fig. 16. This lever has at its centre an elongated transverse slot 69 which engages the upper extremity of 75 the suspension bolt 7 which thereby prevents the lever 68 from moving transversely relative to the track 4. The extremities of the lever 68 which are bent over at right angles are arranged in the path of an abutment 70 carried by the wheel 15.

When this abutment 70 is caused to come into contact with one of the extremities of the lever 68, as shown in Fig. 15, through the operation of the chains actuating the 85 wheels 15 and 16, the lever 68 oscillates about the point 7 and tends to cause the two trolleys 1 and 2 to pivot in a counter-clockwise direction. In view of the fact that the vertical guide rollers 1^a, 1^b and 2^a, 2^b have only 90 a limited amount of play between the rails 4, the trolleys 1 and 2 can only pivot to a very slight extent. As soon as the trolley 2 for example, reaches the curve 71 it can pivot under the effort transmitted by the 95 lever 68, which then pivots around the point 66'', which may be considered as a fixed point since the trolley 1 is always held in place by the rail 4. The crane therefore engages by its two extremities in the branch 100 line 71.

Figs. 17, 18 and 19 correspond to Figs. 1, 2 and 3, but they relate to a bogie composed of two trolleys of the mono-rail type; moreover, Figs. 20 and 21 correspond to Figs. 105 4 and 6 and Figs. 22, 23, 24, 25, 26 and 27 correspond to Figs. 7, 8, 11, 12, 14 and 15 respectively. The same reference letters designate the same members in the two groups of figures and the method of operation 110 is the same in the two groups.

Figs. 28 and 29 show the invention applied under one of its forms to a universal crane having single trolleys of the double rail type 115 at its extremities, the actuating mechanism, the connecting mechanism, and the guide mechanism being identical to that shown in Figs. 1 and 2 and having the same reference letters.

Fig. 30 shows a crane constructed according to Figs. 28 and 29, the main girder 72 being constituted by a single bar upon which are fixed the suspension hooks 73 (Fig. 31).

Figs. 32 and 33 are similar to Figs. 12 and 7 respectively but they show double rail 125 trolleys for each extremity of the crane. The same reference letters which designate the corresponding parts have been retained in the case of Figs. 32 and 33.

The device shown in Figs. 34 and 35 is 130

specially adapted for use with universal cranes having single trolleys. Each end trolley 74, 75 has a prismatic portion 76 which is fixed in position and upon which are keyed two pulleys 77, 78. The pulley 78 receives the actuating chain 21 as in the devices already described. The pulley 77 is grooved or cut like a helicoidal wheel, engaging with a worm, the thread of which is round. The worm is constituted by a helical spring 79 the extremities of which would be welded together in such a manner as to form a kind of endless chain. The pitch of this spring is approximately equal to the pitch of the teeth of the wheel 77. The end of the spring 79 engages with the pulleys 77 which are positively connected thereby.

The method of operation is as follows:

Supposing that the crane moves with its trolleys one behind the other, the direction is given to one of these trolleys by one of the operating chains and the movement of this trolley can take place independently of the other, owing to the fact that the endless spring chain 79 yields in the desired direction. However, the spring 79 tends to resume its normal position and consequently tends to cause the trolley, which has not been actuated directly, to pivot. As soon as this trolley can pivot, that is to say as soon as it reaches the switch in which its predecessor has engaged it pivots under the action of the spring 79 and is therefore obliged to enter the said switch.

In cases where the two trolleys arrive at the same time at two switches acting in the same direction and situated at an equal distance relative to the girder 3, operation of one of the trolleys would compel the other one to deviate into the parallel branch line owing to the connecting spring 79.

Figs. 36, 37, 38, 39 and 40 are similar to Figures 28, 29, 32, 33 and 34 but they relate to the case of universal cranes having single mono-rail trolleys. The parts which correspond in the two groups of figures have been designated by the same reference letters. The method of operation is the same with both of these two groups of figures.

In cases where the universal crane is required to transport heavy loads or when the span becomes great in relation to the end carriage wheel base, it is necessary to distribute the weight over a greater length of the track and for this purpose a greater number of trolleys than two should be used. The invention is applicable also to this case and one of its forms of execution applied to the case in question is shown in Fig. 41. In this figure, the device of Fig. 8 has been supposed to have been extended to the four trolleys 80, 81, 82, 83 connected together by links 85. The two first and the two last trolleys are connected to each other by means of boxes 86, 86' similar to the boxes

6 of the preceding figures. These boxes 86, 86' are suspended to bolts 87 about which the trolleys can pivot. The box 6 of Fig. 8 is suspended to the boxes 86, 86' by means of hollow bolts 88 which are mounted in the same way as the bolt 7 of Fig. 8. Guide rollers 80 carried by the rods 31 are provided at the front of the first trolley and at the rear of the last trolley. Rods 31 are pivoted at their lower extremity on levers 89 which pivot at 90 in the boxes 86, 86' and are each connected to a rod 91 which slides in the bolts 88. The rods 91 are connected to the system of levers enclosed in the box 6 and mounted upon the frame 3 and the point of oscillation 84 of the levers 49 is placed at the extremity of the levers. It will be understood that all the other parts situated in the box 6 and all the parts below this latter in Fig. 41 are analogous to those shown in Fig. 8. The method of operation will be understood from an examination of Fig. 41 in view of what has already been stated relative to Fig. 8. It will be understood that all the necessary clearances are provided in the bearings so as to allow of the individual pivoting of the trolleys and of the boxes 86, 86'.

I claim:

1. The combination with an overhead universal crane comprising a cross-girder and end trolleys pivoted relative to said girder, of manually-operated means for controlling the angular position of the trolleys, and switching means adapted to engage the trolleys.

2. The combination with an overhead universal crane, comprising a cross girder and end trolleys pivoted relative to said girder, of manually operated means at each end of the crane for controlling the angular position of the trolleys and switching means adapted to engage the trolleys.

3. The combination with an overhead universal crane comprising a cross-girder and end trolleys pivoted relative to said girder, of manually operated means at each end of the crane for controlling the angular position of the trolleys, connecting means between said hand-operated means, and switching means adapted to engage the trolleys.

4. The combination with an overhead universal crane comprising a cross-girder and end trolleys pivoted relatively to said girder, of a switching device comprising hand-operated means at each end of the crane for controlling the angular position of the trolleys, connecting means between said hand-operating means for enabling the operation to be effected from either end of the crane and a switching mechanism at each end of the crane, said switching mechanism acting upon the trolleys of said ends.

5. The combination with an overhead universal crane comprising a cross-girder and

end trolleys pivoted relative to said girder, of sprocket-wheels loosely mounted on the axes of suspension of said crane at each end thereof, an endless chain passing round said sprocket-wheels and adapted to be actuated by hand, abutments fixed to said sprocket-wheels, lugs fixed to the frames of said trolleys, said abutments being adapted to encounter said lugs on actuation of the chain to alter the angular position of the trolleys.

6. The combination with an overhead universal crane comprising a cross-girder and end trolleys pivoted relative to said girder, of sprocket-wheels loosely mounted on the axes of suspension of said crane at each end thereof, an endless chain passing round said sprocket-wheels and adapted to be actuated by hand, spring-pressed abutments fixed to said sprocket-wheels, lugs fixed to the frames of said trolleys said abutments being adapted to encounter said lugs on actuation of the chain so that the springs are compressed.

25 7. The combination with an overhead universal crane comprising a cross girder and end trolleys pivoted relative to said girder, of springs acting upon said trolleys, manually operated means for varying the tension of said springs and guide-members into which the trolleys are forced by the springs.

8. The combination with an overhead universal crane comprising a cross-girder and end trolleys pivoted relative to said girder, of rollers mounted on said trolleys, guide-cams fixed adjacent to the track, and manually operated means for moving said rollers into engagement with said cams for the purpose of leading said trolleys into branch-lines.

40 9. The combination with an overhead universal crane comprising a cross-girder and end trolleys pivoted relative to said girder, of rollers mounted on said trolleys, movable rods carrying said rollers, pivoted levers upon which said rods rest, guide-cams fixed adjacent to the track, means actuated by hand for tilting said levers to raise said rollers into contact with said guide-cams for the purpose set forth.

50 10. The combination with an overhead universal crane comprising a cross-girder and end trolleys pivoted relative to said girder, rollers mounted on said trolleys, 55 guide cams fixed adjacent to the track and conjugated means for raising the rollers at each end of the girder into engagement with the guide cams, for the purpose set forth.

60 11. The combination with an overhead universal crane comprising a cross-girder and end trolleys pivoted relative to said girder, rollers mounted on said trolleys, movable rods carrying said rollers, pivoted levers upon which said rods rest, guide cams fixed 65 adjacent to the track, a cable connected to

the other ends of said levers and adapted to pivot them when pulled, to cause said rollers to engage said guide cams, said cable being also connected to the levers at the other end of said girder.

70 12. The combination with an overhead universal crane comprising a cross-girder, and end trolleys pivoted relative to said girder, of rollers mounted on said trolleys, guide cams fixed adjacent to the track, means for moving said rollers into engagement with said guide cams and automatic means for withdrawing them from such engagement.

75 13. The combination with an overhead universal crane comprising a cross-girder and end trolleys pivoted relative to said girder, of rollers mounted on said trolleys, guide cams fixed adjacent to the track, levers engaging said rollers, sprocket wheels mounted on the axis of suspension of the crane at each end thereof, a rotary cam fixed to said sprocket wheels and engaging the ends of said levers and an endless chain passing over said sprocket wheels and adapted to be operated by hand.

80 14. The combination with an overhead universal crane comprising a cross-girder and end trolleys pivoted relative to said girder, of rollers mounted on said trolleys, 95 guide cams fixed adjacent to the track, means for moving the rollers of the trolleys at one end of the girder into engagement with the guide-cams before those at the other and means for automatically disengaging them.

90 15. The combination with an overhead universal crane comprising a cross-girder, and end trolleys pivoted relative to said girder, of rollers mounted on said trolleys, 100 guide cams fixed adjacent to the track, means for moving the roller of the trolleys at one end of the girder into engagement with the guide cams before those at the other and a spring-stop mechanism for controlling the sequence of these operations.

105 16. The combination with an overhead universal crane comprising a cross-girder and end trolleys pivoted relative to said girder, of a sprocket wheel mounted on the 115 axis of suspension of said girder, a lever mounted upon said axis, arms projecting to one side of one trolley and to the opposite side of the other, links connecting said arms to opposite ends of said lever, an abutment 120 on said wheel adapted to contact with said lever when rotated and means for rotating said wheel.

110 17. The combination with an overhead universal crane comprising a cross-girder 125 and end trolleys pivoted relative to said girder, of manually operated means at each end of the crane for controlling the angular position of the trolleys, elastic connecting means between said manually operated 130

means, and switching means adapted to engage the trolleys.

18. The combination with an overhead universal crane comprising a cross-girder and end trolleys pivoted relative to the girder, a pulley on the axis of each trolley, an endless chain connecting the trolleys at each end of the girder, said pulley having

a helicoidally grooved portion, a coil spring fitting said groove and passing round the 10 helicoidal portion and being led round a similar portion on the trolley at the other end of the girder, the ends of said spring being connected together.

CHARLES VINCENT RAPIER.
